Wilcolator Company, Newark, N. J., a corpora-
tion of Delaware

Original application June 23, 1938, Serial No.
215,347. Divided and this application June 30,
1939, Serial No. 282,151

12 Claims. (Cl. 236—99)

This invention relates to valves and more particularly to a novel valve in which the actuating means for the valve member may extend through an opening therein without leakage through the opening when the valve member is seated and without the use of sealing means to prevent such leakage. The new valve is of simple, compact construction and is adapted for manufacture at low cost.

While the valve of the present invention may be used for various purposes, it offers particular advantages when used in temperature regulators, such as an oven regulator, and accordingly an embodiment of the invention suitable for controlling oven temperatures will be described and illustrated in detail. It will be understood, however, that the invention may be used for other purposes as well.

Temperature regulators for gas ovens generally include a casing having gas inlet and outlet ports and a valve in the casing for controlling flow through the outlet port. In one type of gas regulator, the valve member is actuated by an element in the casing which responds to temperature changes in the oven, and the valve member is connected to this element by a rod extending through an opening in the valve member and movable therein to accommodate "overshoot," that is, to permit movement of the thermo-responsive element relative to the valve member after the latter is seated. In regulators of this type as devised heretofore, the valve is generally closed by seating of the valve member on the rim of a central opening in the casing forming a gas passage between the inlet and outlet ports, the passage in some instances also serving to accommodate a valve adjustment shaft which extends through the gas passage from a temperature adjustment handle at the front end of the casing. With this construction, the opening in the valve member through which the rod from the thermo-responsive element extends must be sealed to prevent the passage of gas to the burner when the valve is closed, and the provision of adequate sealing means involves an appreciable item of expense.

One feature of the present invention, therefore, resides in the provision of a novel gas regulator including a valve so constructed that the connection between the thermo-responsive element and the valve member may extend loosely through an opening in the valve member without resulting in leakage when the valve is closed.

An oven regulator made in accordance with the invention comprises a valve for controlling

the supply of fuel to the oven burner, a temperature adjustment handle, and a thermo-responsive element, these parts being preferably arranged in a straight line relation with the handle and the thermo-responsive element at opposite ends of a casing and the valve intermediate the ends of the casing. The valve is operable by the thermo-responsive element through a connection projecting through an opening in the valve member and slidably therein to accommodate over-shoot, and the connection is preferably adjustable by a shaft extending from the adjustment handle through a passage in the casing which leads to the valve. However, this passage is separate from the gas passage in the valve seat, the gas passage being offset laterally from the first passage. Preferably, the gas passage surrounds the passage for the adjustment shaft and is separated therefrom by an annular part of the casing, and when the valve is closed, the valve member seats against this annular part and thus closes the end of the gas passage from the opening in the valve member and from the corresponding end of the passage for the adjustment shaft. Accordingly, when the valve member is seated the passage of gas between the inlet and outlet ports is prevented, irrespective of the fit between the valve member and the connection extending therethrough.

For a better understanding of the invention reference may be had to the accompanying drawing, in which

Fig. 1 is a longitudinal sectional view of one form of the new regulator, and

Figs. 2 and 3 are reduced sectional views on the lines 2—2 and 3—3 in Fig. 1.

The valve of the regulator is illustrated in conjunction with my new valve sub-assembly including the movable element of the valve, a bimetallic compensator and a temperature adjustment means for the valve, which sub-assembly is removable from the regulator as a unit. This sub-assembly is described in my copending application Serial No. 215,347, filed June 23, 1938. The new regulator, as shown, comprises a housing including a hollow, rear section 10 secured to a front section 11 to form a main chamber 12. Preferably, packing 13 is interposed between the housing sections to make the chamber gas-tight. A passage 14 extends forwardly from the chamber 12 through a hollow boss 15 at the front end of the housing, and adjacent the passage 14 is a gas passage 16 which leads into the main chamber. The passage 16, as illustrated, is annular and is disposed in the front section 11 concen-

tric with the passage 14 so that the passages are separated by an annular wall 17. At its end, the wall 17 is provided with a sharp annular rim 18 which coacts with a similar concentric rim 19 to form a double seat at the mouth of the passage 16 for a valve member 20. The casing is provided with an inlet 21 for admitting gas to the annular passage 16, and the valve member 20 and the seat 18-19 together form a control means for regulating the flow of gas from passage 16 through the chamber 12 to an outlet port 22 in the casing, which may be connected to an oven burner (not shown).

The valve member 20 is movable by thermo-responsive means which may take various forms but preferably comprises a bellows 23 sealed within a cup 24 connected to the rear end of the casing by bolts 25, the bellows and cup together forming an expandable and contractible chamber 26. The open end of the cup 24 is sealed to the casing by an annulus 27 interposed between the rear end of the casing and a flange 24' on the cup. At its rear end, the cup 24 has an opening in which one end of a capillary tube 28 is sealed, the tube leading from the chamber 26 to a bulb (not shown) adapted to be located in the oven. The bulb, tube and chamber 26 are filled with a thermo-responsive liquid, such as chlorinated diphenol. A headed pin 30 is seated against the end of the bellows and extends forwardly into chamber 12 through the annulus 27 and a central opening in the rear end of the casing, the front end of the pin being reduced, as shown at 30'. A spring 31 coiled around pin 30 bears at one end against the rear end of the casing and at the opposite end against the head of the pin and tends to expand the bellows and compress the liquid in chamber 26.

The valve member 20 is operable by pin 30 through a suitable connection which, as shown, comprises a metal strap 32 disposed in chamber 12 and formed with a central opening through which the reduced end 30' of pin 30 extends, the strap being normally seated against a shoulder 33 on the pin adjacent the reduced end thereof. The ends of strap 32 are inclined forwardly relative to the central portion thereof and are reduced in width at their extremities to form lugs 34. A strip of corrugated bimetal 35 is seated in front of the strap 32 against the inclined ends thereof and is provided with lugs 36 similar to the lugs 34, the lugs 34 and 36 extending through openings in the legs of a U-shaped retainer 37 made of spring metal. The ends of the retainer are bent backwardly and its intermediate portion has an opening through which a square, headed rod 38 extends, the head of the rod engaging the rear face of retainer 37 and normally bearing against the central corrugation of the strip 35.

The rod 38 extends forwardly through a central opening in valve member 20 and is formed at its front end with a reduced, threaded portion 38'. The rod fits relatively loosely in the opening in the valve member, and the edges of the opening are rounded so that the valve member may adjust itself on the rod to seat properly on the valve seat 18-19. Coiled around the rod 38 is a spring 39 which bears at one end against the retainer 37 and at the opposite end against the valve member 20. An adjustment nut 40 threaded on the reduced end of the rod normally engages the front face of valve member

20 and may be screwed on the rod to adjust the valve member.

The nut 40 is adjustable on rod 38 by adjustment means which preferably comprises a hollow shaft 42 extending through the passage 14 and the hollow boss 15 and rotatable by a temperature adjustment dial 43 in front of the housing. A shoulder 44 on the shaft normally engages a coacting shoulder in the passage 14, thereby determining the axial position of the shaft in the casing. At its inner end, the shaft 42 is formed with longitudinal slots 42' into which a plurality of radial lugs 40' on the adjustment nut 40 extend. A coil spring 45 in the shaft is seated at one end against the internal face of shoulder 44 and at its opposite end against the nut and serves the dual function of urging the strap 32 against shoulder 33 and taking up any looseness of the nut on rod 38.

When the oven is not in use, the dial 45 is in its "off" position wherein the nut 40 is disposed near the left end of the rod 38 and the spring 39 urges the valve member against its seat. In starting the oven, the dial is turned so as to rotate the shaft and screw the nut 40 to the right, as seen in Fig. 1. The nut thus forces the valve member away from its seat along the pin 38 against the action of the spring, the distance through which the valve member is moved being determined by the desired temperature setting of the dial. As the oven commences to heat, the expansion of the liquid in the bulb causes the bellows to collapse, and as a result, the pin 30 acts through the strap 32, the bimetallic strip 35 and the rod 38 to move the nut 40 to the left. The valve member is, therefore, moved toward its seat and throttles the flow of gas from the inlet 21 to the oven burner. When the temperature of the oven corresponds to the temperature for which the dial is set, the valve member is held in a throttling position in which it allows just enough gas to pass to the burner to maintain the oven at the desired temperature. Thereafter, any cooling of the oven causes the bellows to expand, whereby the spring 45 moves rod 38 and the valve member to the right to admit a greater amount of gas to the burner.

If the oven temperature should rise above the temperature for which the dial is set, the valve member is moved by the bellows against the seat 18-19 so as to cut off the flow of gas to the burner. If the chamber 26 should then continue to expand for any reason, the rod 38 is moved to the left through the valve member so as to disengage the nut from the valve member and compress the springs 39 and 45. When the oven cools, the contraction of chamber 26 allows spring 45 to move the rod to the right and re-engage the nut with the valve member, after which further contraction of the chamber causes the rod and the nut to move the valve member away from the seat. It will be apparent that in adjusting the regulator from a high temperature setting to a lower one, the dial is turned so as to screw the nut 40 outwardly on rod 38, whereby the spring 39 moves the valve member along the rod toward the seat.

In some installations, the regulator may be mounted on a range near an open burner which might heat and expand the liquid in chamber 26. Such expansion of the liquid would cause a false actuation of the valve, unless suitable provision were made to counteract the action of the external heat. In the new regulator, when the liquid in chamber 26 expands due to external

heat thereby urging pin 30 to the left, the bimetallic strip 35 bows so that the intermediate portion thereof moves to the right. Since the spring 45 and the retainer 37 urge the head of rod 38 against strip 35, the rod follows the intermediate portion of the strip to the right and compensates for the liquid expansion in chamber 26. When the external heat source permits the liquid in chamber 26 to cool, causing pin 30 to move to the right, the compensating strip 35 bows in the opposite direction so as to force the head of pin 38 to the left an equal amount.

If desired, the oven may be provided with a pilot (not shown) supplied with gas by a pipe 47 threaded in one side of the housing and communicating through a transverse passage 48 with gas passage 16. The supply of gas from passage 16 to the pilot may be adjusted by a screw 49 extending transversely through the passage 48, that is, lengthwise of the housing. The screw 49 is provided with shoulders 50 and 50' at opposite ends of the threaded portion thereof, and these shoulders coact with shoulders in the casing to form grease or packing chambers acting as a double seal. A bypass 52 may be provided in the casing between the annular passage 16 and the main chamber 12, and the flow of gas through the bypass may be regulated by an adjustment screw 53 similar to screw 49.

It will be apparent that by reason of the double valve seat 18-19, the rod 38 may be fitted relatively loosely in the valve member 20, because when the valve member is seated it closes the gas passage 16 in the valve seat from the central opening in the valve member. Thus, the new regulator is provided with an adjustable connection extending through the valve member from the thermo-responsive element, but does not require the usual means for sealing the opening in the valve member around this connection to prevent leakage when the valve is closed. By removing the hollow section 10 of the housing from the front section, the rod 38, the valve member and the adjustment nut may be removed as a unit to permit cleaning of the valve.

I claim:

1. In a valve, a housing having a chamber therein, a recess in a wall of the chamber, and a fluid passage terminating in a valve seat adjacent the recess, a valve member coacting with the seat and having an opening therein overlying the recess, the valve member being operable when seated to close the fluid passage from said recess and opening, and an actuating element for moving the valve member relative to the seat, said element extending through said opening and being movable through the valve member into the recess when the valve member is seated.

2. In a valve, a housing having a chamber therein, a recess in a wall of the chamber, and a fluid passage terminating in a valve seat adjacent the recess, a valve member coacting with the seat and having an opening therein overlying the recess, the valve member being operable when seated to close the fluid passage from said recess and opening, an actuating element extending through said opening and operable to move the valve member to the seat, said element being movable through the valve member into said recess when the valve member is seated, and means in the recess for adjusting the valve member relative to the seat and the actuating element.

3. In a valve, a housing having a chamber

therein, a recess in a wall of the chamber, and a fluid passage terminating in a valve seat adjacent the recess, a valve member coacting with the seat and having an opening therein overlying the recess, the valve member being operable when seated to close the fluid passage from said recess and opening, an actuating element extending through said opening and operable to move the valve member relative to the seat, said element being movable through the valve member into said recess when the valve member is seated, and an adjustment nut in the recess threaded on the actuating element for moving the valve member relative to the seat and said element.

4. In a valve, a housing having a chamber therein, a recess in a wall of the chamber, and a fluid passage terminating in a valve seat adjacent the recess, a valve member coacting with the seat and having an opening therein overlying the recess, the valve member being operable when seated to close the fluid passage from said recess and opening, an actuating element extending through said opening and operable to move the valve member relative to the seat, said element being movable through the valve member into said recess when the valve member is seated, a member in the recess threaded on said element and operable to adjust the valve member relative to the seat and said element, and a spring urging the valve member toward said threaded member.

5. A valve comprising a valve body having a bore therein and a fluid passage substantially surrounding the bore and separated therefrom, a valve member for closing one end of the passage and having an opening therein overlying the bore when the valve member is seated, an actuating element extending through said opening and movable therein, and means in the bore for adjusting the valve member on said element.

6. In a fluid regulator, a housing having a bore therein and a fluid passage disposed around the wall of the bore and terminating in a double seat adjacent one end of the bore, a valve member coacting with the seat and having an opening therein, the valve member being operable when seated to close the passage from said opening and the adjacent end of the bore, and a thermo-responsive element extending through said opening for moving the valve member, said element being movable through the opening when the valve member is seated.

7. In a fluid regulator, a housing having a bore therein and a fluid passage disposed around the wall of the bore and terminating in a double seat adjacent one end of the bore, a valve member coacting with the seat and having an opening therein, the valve member being operable when seated to close the passage from said opening and the adjacent end of the bore, a thermo-responsive element extending through said opening for moving the valve member, said element being movable through the opening when the valve member is seated, an abutment in the bore disposed on said element and engageable with the valve member to move said member away from the seat, and a spring urging the valve member against said abutment.

8. In a fluid regulator, a housing having a bore therein and a fluid passage disposed around the wall of the bore and terminating in a double seat adjacent one end of the bore, a valve member coacting with the seat and having an opening therein, the valve member being operable when seated to close the passage from said opening and the adjacent end of the bore, a thermo-

responsive element extending through said opening for moving the valve member, said element being movable through the opening when the valve member is seated, an abutment in the bore disposed on said element and engageable with the valve member to move said member away from the seat, and a spring in the bore normally urging said abutment toward the valve member.

9. In a fluid regulator, a housing having a bore therein and a fluid passage disposed around the wall of the bore and terminating in a double seat adjacent one end of the bore, a valve member coacting with the seat and having an opening therein, the valve member being operable when seated to close the passage from said opening and the adjacent end of the bore, a thermo-responsive element extending through said opening for moving the valve member, said element being movable through the opening when the valve member is seated, an abutment in the bore adjustable on said element and engageable with the valve member to move said member away from the seat, a shaft rotatable in the bore to adjust said abutment and projecting through the front of the housing, and a temperature adjustment handle mounted on the shaft.

10. In a fluid regulator, a housing having a chamber therein and a bore leading into the chamber, the housing also having a fluid passage disposed around the wall of the bore and terminating in a double seat in the chamber adjacent one end of the bore, a valve member coacting with the seat and having an opening therein overlying the bore, said member being operable when seated to close the passage from the chamber, an actuating element extending through said opening for moving the valve member relative to the seat, said element being movable through the opening into the bore when the valve member is seated, and a bypass extending radially

from said passage and terminating in the chamber outwardly from the valve seat.

11. In a valve, a housing having an annular passage and a second passage within the inner wall of the annular passage, the inner and outer walls of the annular passage terminating in a double seat, a valve member engageable with the seat to close the annular passage from said second passage, a valve stem extending through the valve member into the second passage and movable through the valve member when said member is seated, an abutment on the stem disposed in the second passage and engageable with the valve member to move the member away from the seat, a spring for urging the valve member against the abutment, and means extending through the second passage for adjusting the position of the abutment on the stem to vary the setting of the valve member.

12. In a valve, a housing having an annular passage and a second passage within the inner wall of the annular passage, the inner and outer walls of the annular passage terminating in a double seat, a valve member engageable with the seat to close the annular passage from said second passage, a valve stem extending through the valve member into the second passage and movable through the valve member when said member is seated, an abutment on the stem disposed in the second passage and engageable with the valve member to move the member away from the seat, a spring for urging the valve member against the abutment, and a rotatable shaft extending through the second passage and sealing the same, the shaft being connected to the abutment and being operable to adjust the position of the abutment on the stem to vary the setting of the valve member.

BENSON F. WADDELL.
